ADAPTER FOR INCANDESCENT ELECTRIC
LAMP BASESJohn W. Hipelius, Chicago, Ill., assignor to Bell
& Howell Company, Chicago, Ill., a corporation
of Illinois

Application January 7, 1949, Serial No. 69,770

4 Claims. (Cl. 173—344)

1

My invention relates to an adapter for incandescent lamp bases of the type disclosed and claimed in the co-pending U. S. patent application of Albert S. Howell, Serial No. 757,435, filed June 27, 1947, now Patent No. 2,504,419, issued April 18, 1950, for improvement on Incandescent Electric Lamp, Socket, Lamp, and Adapter Therefor, and objects of the invention reside in the provision of an adapter of the above type which may be considered an improvement on the adapter of said application, which is of simple construction and susceptible of economical quantity manufacture, which provides for adequate ventilation through a socket of the type disclosed in said application and by the base of a lamp installed in the socket, which provides for accurate and rigid positioning of the lamp in the socket, which provides for adapting the conventional base of an incandescent electric lamp for the socket disclosed in said application, and which provides for conveniently attaching the adapter to a lamp base in a neat and unobtrusive manner.

A further object of the invention resides in the provision of a method of producing the adapter of my invention which is economical and adapted for quantity production.

The invention will be better understood by reference to the accompanying drawing forming a part hereof and in which—

Figure 1 is a vertical sectional view of an incandescent electric lamp socket having an incandescent electric lamp, equipped with the adapter of my invention, installed therein;

Figure 2 is a top plan view of the same with the center contact assembly of the socket removed;

Figure 3 is a perspective view of the adapter of my invention; and

Figure 4 is a plan view of the blank from which the adapter is formed in accordance with the method of my invention.

Referring to the drawing, a main lamp socket part or body 1, see Figures 1 and 2, of molded insulating material is provided with a large vertical bore 2 therethrough, and molded in the body 1 and disposed in coaxial relation with the bore 2 is an annular metal contact member 3 having the same internal diameter as that of the bore 2. The body 1 is provided at the bore 2 with three recesses 4, 5 and 6 angularly spaced about the axis of the bore in circumscribing relation therewith and extending downwardly to the contact member 3 and exposing corresponding portions of the upper surface of the same to form upwardly facing contact portions, the recess 6 being of

2

greater extent angularly of the bore 2 than the recesses 4 and 5 for a purpose hereinafter appearing.

The socket body 1 and the contact member 3 are adapted to have the body 1 of an incandescent electric lamp 8 passed downwardly through the bores thereof, and the base of the lamp is provided with a circumferential metallic contact, comprising the adapter of my invention and generally designated at 9, arranged angularly about the lamp base axis and extending laterally thereof outwardly beyond the lamp body and adapted to engage in the recesses 4, 5 and 6 and downwardly on the contact member 3 to position the lamp, the adapter 9 being of generally annular character and engaged about and secured, as hereinafter described, to the usual outer cylindrical conductive member 11 of the usual base of the lamp and insulated from the usual conductive end contact 12 of the lamp base.

A socket cap 13 of insulating material carries a conductive end contact 14 which is spring urged, as by a spring 15 operative between the cap and this end contact, into contact with the end contact 12 of the lamp base when the cap is in position overlying the socket body 1, as shown in Figure 1, to maintain the end contact 14 in contact with the end contact 12 and to maintain the lamp in the socket with the contact member 9 in contact with the contact member 3. The cap 13 is releasably secured in this position and is pivotally mounted on the socket body, by means unnecessary to be described, for movement from the position shown in Figure 1 to a position permitting insertion of the lamp in the removal of the lamp from the socket body.

The adapter of my invention forming the contact member 9 of the lamp base, see Figures 1, 2 and 3, comprised as follows:

A substantially hexagonal collar, see particularly Figure 3, has alternate long and short sides and the triangularly related long sides 16 thereof form arms and have their intermediate portions engageable with the outer cylindrical conductive member 11 of the lamp base for securing thereto. The sides of the collar are of greater width than thickness and the short sides 17, 18 and 19 thereof are disposed with their widths extending in the plane of the contact member 9, and the long sides are disposed with their widths extending transversely of said plane, thus providing a structure of skeletal character which possesses relatively great rigidity.

The short sides of the adapter constitute contact portions and to this end the short sides 17

and 18 are provided with contact tongues 21 and the short side 19, which is of greater angular extent than the short sides 17 and 18, is provided with two spaced contact tongues 22 respectively disposed at the ends of this short side, and the contact tongues 21 and 22 extend outwardly from the short sides. The short side 19 is also provided at its outer portion with an additional tongue 23 which extends therefrom transversely of the plane of the adapter. Preferably as shown, the widths of the long sides 16 extend transversely of the plane of the adapter in one direction from the short sides 17, 18 and 19 and the tongue 23 extends transversely of said plane in the other direction from the short sides. 15

The adapter being engaged about the outer cylindrical conductive member 11 of the lamp base with the intermediate portions of the arms 16 engaging the same, the intermediate portions of the arms 16 are secured to the contact member as by solder with the adapter in adjusted relation with the filament of the lamp, and to provide for conveniently soldering the adapter to the conductive member 11 of the lamp base and to provide a neat unobtrusive solder joint between the adapter and this conductive member, the intermediate portions of the arms 16 of the adapter are provided with inwardly facing recesses 24, preferably formed by extrusion, into which solder 25 in the form of pellets are engaged before the adapter is engaged on the conductive member 11 and in which the solder is mainly confined during the fusion thereof with the adapter and conductive member 11. 30

As shown, the adapter is secured on the lamp base with the tongue 23 extending in the direction of the lamp body 7, and is engageable in a vertical slot 26 through the contact member 3 at the intermediate portion of the recess 6. 35

When the lamp 8 is mounted in the socket body 1, as shown in Figures 1 and 2, the contact tongues 21 are respectively engaged in the recesses 4 and 5 and the contact tongues 22 are engaged in the recess 6 which is of greater angular extent than the recesses 4 and 5 to accommodate the tongues 22 and 23, and the tongue 23 being engaged in the slot 26 to locate the lamp angularly in the socket body, the tongues 21 and 22 engage downwardly on the contact member 3 and accurately locate the lamp, the tongues being held in such engagement by downward pressure of the spring urged end socket contact 14 upon the end contact 12 of the lamp base. The widths of the arms 16 of the adapter being disposed transversely to the plane of the adapter, their widths extend longitudinally of the socket body and lamp so that they provide air passage of relatively great area through the socket body and by the lamp base for adequately cooling the same by an air current through the socket body and by the lamp base. 45

The adapter is preferably produced by the method of my invention which comprises as follows:

A collar 27, see Figure 4, is blanked, as by means of a blanking die, from conductive sheet material such as sheet metal. The collar, as so blanked, is of generally hexagonal form having the alternate long sides 16 and short sides 17, 18 and 19 of appreciably greater width than thickness, the contact tongues 21 and 22 and the tongue 23 of the adapter of Figure 3 in a common plane but otherwise all related as above described with reference to the adapter 9 of Figure 3. Preferably, the recesses 24 are formed in

the intermediate portions of the long sides 16 of the blank before the blank is formed into the adapter. The collar 27 having been so blanked, the long sides 16 and the tongue 23 are bent with respect to the short sides 17, 18 and 19 facewise of the blank, as by means of a forming die, into transverse relation with the plane of the adapter and the short sides 17, 18 and 19, thus forming the adapter 9 of Figure 3. 5

While I have thus described my invention, I do not wish to be limited to the precise details described, as changes may be readily made without departing from the spirit of my invention, but having thus described my invention, I claim as new and desire to secure by Letters Patent the following:

1. An adapter in the form of a conductive contact member of generally annular character adapted to be engaged about and secured to an outer cylindrical conductive member of an incandescent lamp base, comprising a substantially hexagonal collar having alternate long and short sides and the long sides of which form arms and have their intermediate portions engageable with said cylindrical conductive member for securing thereto, and said sides being of greater width than thickness and said short sides being disposed with their widths extending in the plane of the contact member and said long sides being disposed with their widths extending transversely of said plane. 20

2. An adapter in the form of a conductive contact member of generally annular character adapted to be engaged about and secured to an outer cylindrical conductive member of an incandescent lamp base, comprising a substantially hexagonal collar having alternate long and short sides and the long sides of which form arms and have their intermediate portions engageable with said cylindrical conductive member for securing thereto, said sides being of greater width than thickness and said short sides being disposed with their widths extending in the plane of the contact member and provided with contact tongues extending outwardly therefrom, and said long sides being disposed with their widths extending transversely of said plane. 30

3. An adapter in the form of a conductive contact member of generally annular character adapted to be engaged about and secured to an outer cylindrical conductive member of an incandescent lamp base, comprising a substantially hexagonal collar having alternate long and short sides and the long sides of which form arms and have their intermediate portions engageable with said cylindrical conductive member for securing thereto, said sides being of greater width than thickness and said short sides being disposed with their widths extending in the plane of the contact member and one of said short sides being provided at its outer portion with a tongue extending therefrom transversely of said plane, and said long sides being disposed with their widths extending transversely of said plane. 40

4. An adapter in the form of a conductive contact member of generally annular character adapted to be engaged about and secured to an outer cylindrical conductive member of an incandescent lamp base, comprising a substantially hexagonal collar having alternate long and short sides and the long sides of which form arms and have their intermediate portions engageable with said cylindrical conductive member for securing thereto, said sides being of greater width than thickness and said short sides being disposed with

their widths extending in the plane of the contact member and said short sides being provided with contact tongues extending outwardly therefrom and one of said short sides being provided at its outer portion with an additional tongue extending therefrom transversely of said plane, and said long sides being disposed with their widths extending transversely of said plane.

JOHN W. HIPELIUS.
